[57] **CLAIM**

The ornamental design for a disposable electrochemical measurement cartridge for a portable medical analyzer, as shown and described.

DESCRIPTION

FIG. 1 is a perspective view of a disposable electrochemical measurement cartridge for a portable medical analyzer showing our new design;

FIG. 2 is a top plan view of the disposable electrochemical cartridge for a portable medical analyzer;

FIG. 3 is a bottom plan view of the disposable electrochemical measurement cartridge for a portable medical analyzer;

FIG. 4 is a front elevational view of the disposable electrochemical cartridge for a portable medical analyzer of FIG. 2;

FIG. 5 is a rear elevational view of the disposable electrochemical measurement cartridge for a portable medical analyzer of FIG. 2;

FIG. 6 is a right-side elevational view of the disposable electrochemical measurement cartridge for a portable medical analyzer of FIG. 2; and,

FIG. 7 is a left-side elevational view of the disposable electrochemical measurement cartridge for a portable medical analyzer of FIG. 2.
